SAFETY APPLIANCE FOR BLOCK-SIGNAL SYSTEMS.

1,116,316.

Specification of Letters Patent.

Patented Nov. 3, 1914.

Application filed December 15, 1913. Serial No. 806,852.

To all whom it may concern:

Be it known that I, STEPHEN A. MISCHANSKY, a subject of the Emperor of Austria-Hungary, of Syracuse, in the county of 5 Onondaga, in the State of New York, have invented new and useful Improvements in Safety Appliances for Block-Signal Systems, of which the following, taken in connection with the accompanying drawings, 10 is a full, clear, and exact description.

This invention relates to certain improvements in safety appliances for railway block signal systems and is adapted to be used more particularly in connection with double 15 track railways in which the trains on one track move generally in one direction while those on the opposite track move generally in the opposite direction.

The primary object is to prevent collision 20 between two trains moving in the same direction, or in case one train moving along its track should be inadvertently shifted to the other track to warn the engineer of such fact and thereby prevent head-on collision.

25 One of the specific objects is to provide means actuated by a train passing through any one of the blocks for causing a signal to be operated in the cab of another train in case it should enter that block within a 30 predetermined time after the previously mentioned train has passed through such block.

A further object is to prevent head-on collisions in case a train should inadvertently 35 get on the wrong track by causing certain devices on said train to come into operative contact with the other devices along the track for causing a signal to be operated in the driver's cab of said train.

40 Other objects and uses will be brought out in the following description.

In the drawings, Figure 1 is a perspective view of a portion of a railway track, showing one of the signal-operating devices with which each block of the railway 45 is equipped. Fig. 2 is a top plan of the signal-tripping abutments of levers located in one of the blocks and the positions of portions of the signal-operating members in 50 full lines of a train approaching from the rear in full and from the front by dotted lines. Fig. 3 is a side elevation of a portion of a locomotive, signal-operating device located in the cab thereof, and a portion 55 of the mechanism for operating the

signals. Fig. 4 is a vertical sectional view of the motor-actuated resetting mechanism for the signal-tripping abutments. Fig. 5 is an enlarged face view of the abutment-operating roller and signal-operating members on the underside of the locomotive near the fender. Fig. 6 is an enlarged detail view of the electric switch controlling the operation of the motor. Fig. 7 is a side elevation, partly in section, of the electric switch-controlling operation of the bell signal in the locomotive cab and one of the members for controlling the operation of the drop annunciator which may be used in connection with the audible signal. Fig. 75 60 Fig. 8 is an enlarged detail sectional view of the connections between the signal tripping abutments and its rock-shaft shown in Fig. 1. Fig. 9 is an enlarged face view of the drop annunciator showing one of the shutters as opened to reveal the reading "Front 70 danger" on the inclosed back-plate. Fig. 10 is a detail view of a portion of one of the gears of the motor-operated train shown in Figs. 1 and 4, illustrating the movable 80 contact member thereon for tripping the holding pawl or detent for the switch operating means on the motor.

In order that my invention may be clearly understood, I have shown in Figs. 1 and 2 a portion of one of the blocks of a railway —a— as equipped with a pair of levers or rock-arms —1— and —2— secured at one end to a rock-shaft —3— having one end journaled in a suitable support —4— which 85 is provided with lengthwise recesses for receiving the rock-arms —1— and —2—. These rock-arms extend in opposite directions from their points of connection with the rock shaft —2— and are, together with 90 their support —4—, preferably arranged between and lengthwise of the rails of the track —a—, the recesses in the support being of sufficient depth to allow the upper faces of the rock-arms —2— to lie substantially 95 coincident with the upper face of the support when depressed to their extreme limits of downward movement, the upper faces or edges of the rock arms being disposed in planes at an obtuse angle so that when one 100 of them, as the rock arm —1—, is in its normal depressed position substantially flush with the upper face of the support —4—, the other will be disposed in an inclined position to such face, thereby caus- 105 110

ing its free end to project some distance above the support —4—. These rock arms —1— and —2— are arranged side by side in different lines parallel with the track 5 along which the trains are presumed to move in the direction indicated by arrow —X—, Fig. 1, so that the normally depressed crank arm —1— extends in the opposite direction while the rock arm —2— extends in 10 the same direction as the moving train so that when a train is passing through this block over the rocking members —1— and —2—, one of the operating members, presently described, on the engine will ride 15 along and upon the upper face of the arm —2—, thereby depressing that arm and at the same time, raising the other arm —1— to an inclined position and also rocking the shaft —3— to effect the closing of a motor- 20 controlling switch also located in the same block.

The rock shaft —3— extends from the rock-arms —1— and —2— laterally under and beyond one of the rails some distance 25 to the outside of the track where it is journaled in a suitable bearing —10— on a stationary upright support —11— and is provided with a crank-arm —12—. This crank- 30 arm —12— is connected by a link —13— to the intermediate portion of a rock arm —14— having one end journaled in suitable bearings in a gear-case or housing —15— on the post —11— and its other end pivotally connected to a vertically movable plunger —16— carrying one or more of the terminals of an electric switch —17— having 35 its coöperative terminals mounted upon a stationary support and guide —18— on the interior of the case or housing —15—. 40 The switch-operating plunger —16— is guided in a bracket —18— and an additional guide —19— and when released is spring-pressed upwardly by a coil spring —20— to open the switch, but is adapted to 45 be drawn downwardly against the action of said spring by the depression of the rock-arm —2— through the medium of the rock- 50 shaft —3—, crank arm —12—, link —13— and rock arm —14— to close the electric switch —17— which is connected in a motor circuit to control the action of an electric motor —21— also mounted within the housing —15— upon a supporting bracket —22—.

55 The armature shaft of the motor is connected by a belt —23— to a pulley —24— on one end of a worm shaft —25— carrying a worm —26—, which meshes with a worm gear —27—, the latter forming a part 60 of a gear train —28— within the housing —15— for the purpose of tripping a holding pawl or detent —29— by which the plunger —16— is temporarily held for a predetermined interval of time in its normal 65 down position as effected by the depression

of the rock arm —2— through the medium of a roller —30— on the underside of an engine truck —b— preferably just at the rear of the fender as —b'—.

The pawl or detent —29— is fulcrumed 70 or pivoted intermediate its ends to the bracket —18— and is forced to its holding position by a spring —32—, the lower end of the pawl being provided with a cam —33— adapted to be engaged by a roller or 75 equivalent contact member —34— on the adjacent gear of the train —28— for tripping said pawl at the end of one revolution of said gear for the purpose of releasing the plunger —16— and allowing it to be 80 forced upwardly by the spring —20— to open the switch —17—, thereby breaking the motor circuit and stopping the motor.

The gears of the train —29— are so proportioned as to cause the gear carrying the 85 contact member —34— to rotate very slowly to allow the lapse of a considerable interval of time for each revolution, in this instance approximately one-fourth hour or sufficient to permit the moving train to pass 90 out of the block and into the next succeeding block.

As shown more clearly in Fig. 10, the roller —34— is mounted upon a rock arm —35— which is pivoted at —36— to the adjacent gear and is yieldingly held against the stop —37— by a spring —38—, the object of which is to allow the contact roller to be shifted upwardly against the action of the spring —38— by the cam —33— so as to 100 release the pawl —29— in case the motor should stop with the roller —34— on the point of the cam although in practice it is found that the momentum of the gear —28— will be sufficient to carry the roller 105 —34— beyond the cam point after the motor switch is open.

The operation of my invention as thus far described is as follows: Assuming that the parts shown in Fig. 1 are in their normal 110 positions with the rock arm —1— depressed and the rock-arm —2— elevated, then if a train moves in a predetermined direction indicated by arrow —X— through the block, the contact member or roller —30— 115 on the engine, shown more clearly in Fig. 3, will come in contact with and depress the rock arm —2— and thereby rock the shaft —3— and raise the rock arm —1— by which operation the plunger —16— will be drawn 120 downwardly by means of the crank —12— and link —13— and lever —14— until engaged by the holding pawl or detent —29—, thereby closing the switch —17— and starting the motor —21— to drive the train of 125 gears —28— in the direction indicated by arrow —Y—, Fig. 1. This causes the contact member —34— to be moved slowly but bodily one complete revolution or until the contact roller —34— returns into engage. 130

ment with the cam —33— of the holding pawl —39—, thereby tripping said pawl from holding engagement with the plunger —16— and allowing said plunger to be 5 forced upwardly by its spring —20— to open the switch —17— and stop the motor and train of gears actuated thereby.

As previously stated, the period of time between the closing and opening of the electric switch, during which the motor is operated, may be predetermined and is sufficiently long to allow the train, which has operated the motor switch to pass out of the block, but in case another train should approach from the rear while the first named train is still in the block or before the motor has stopped, and while the rock arm —1— is elevated, the end of the rock arm would be engaged by a pendant arm or 15 finger —39— on the underside of the locomotive and at one side of the roller —30— for operating another electric switch —40— on the engine to close an electric circuit —41— through an electric bell or equivalent 20 signal —42—, thereby warning the engineer or other attendants on the engine that they are approaching another train ahead so that the driver on the following train may slacken his speed and proceed with caution. 25

I may in some instances use a visual signal as a drop annunciator —41—, shown more clearly in Figs. 3 and 9, which may be used with or without the audible signal —42— and consists of a shutter —45— 30 slideable vertically across an opening —46— in a case —47— to alternately cover and reveal a sign at the rear of the opening bearing the words, in this instance "Front danger" and meaning that there is a train ahead, 35 said card or shutter —45— being normally held in its closed position by a pawl or detent —48—. This pawl or detent —48— is pivoted at —49— to the upper portion of the case —47— above the opening —46—, 40 and is provided at one end with a hook —50— for interlocking engagement with a corresponding shoulder —51— on the upper edge of the shutter —45—, the opposite end of the detent being connected by a cord —52— to an apertured arm —53— on the 45 operating member —39—.

In order to prevent head on collisions by a train which might inadvertently get on the track —a— moving in a direction opposite to that indicated by arrow —X—, I have provided the engine with another signal-operating member —55— arranged at the side of and in close proximity to the signal operating member —39— and adapted to come in contact with the raised end of the rock arm —2— between the rails of the track, said end being of sufficient width to engage both of the signal-operating members —39— and —55— for the purpose of 60 operating in addition to the shutter —45— 65

another shutter —45'— which is operated in substantially the same manner as the shutter —51— through the medium of a cord —56— having one end connected to a pawl or detent —48'— and its other end connected to 70 an apertured arm —53'— on the signal-operating member —55— as shown more clearly in Fig. 5 so that both shutters —45— and —45'— may be opened simultaneously by contact of the members —39— and —55— 75 with the widened end of the rock arm —2— to warn the driver of the train, which is on the wrong track, that he is in danger of head-on collision with another train moving in its regular direction on said track. After 80 these shutters —45— and —45'— have been operated, they may be returned by hand to their normal positions into holding engagement with their respective pawls —48— and —48'—.

One of the terminals of the electric switch —40— is movable and normally spring-pressed into engagement with a shoulder —60— on the signal-operating member —39— by means of a spring —61— for 90 moving said terminal into and out of contact with its corresponding terminal on the supporting frame for the members —30—, —39— and —55— as shown more clearly in Figs. 5 and 7. This supporting frame, as 95 —62—, for the signal-operating members is preferably secured to the rear face of the fender —b'— of the engine, the rock arm —2— being disposed in the path of movement of the roller —30— while the rock arm —1— is disposed in the path of movement of the signal-operating member —39— when the train is moving in its regular direction indicated by arrow —X— while the signal-operating member —55— is positioned so as 100 to contact with the end of the rock arm —2— in case an engine or train should be traveling along the track in the opposite direction which would cause the operation of the signals in the locomotive cab as the train passes through each block, thereby 105 warning the engineer to proceed cautiously if he should persist in traveling upon that track.

What I claim is:

1. In a safety appliance for railway block systems, a normally open electric switch located at the block, co-operative contact members on a train and track respectively, the contact member on the track being adapted to be operated by that on the train, means actuated by the operation of the contact member on the track for closing the electric switch, additional co-operative contact members on the train and track respectively, means actuated by the operation of the first named contact member on the track for moving the second contact member on said track into position to be engaged by its co-operative contact member on the train, an 115

120

125

130

electric motor operated by the closing of the switch, and means actuated by said motor for releasing the switch and allowing it to open to stop the electric motor, and additional means actuated by the means which opens the switch for restoring the contact members on the track to their normal positions after a predetermined interval of time.

2. In a safety appliance for railway block systems in combination with a track and train moving along the track, a signal on the train, a signal-operating member on the track normally out of operative position, coöperative contact members on the train and track respectively for moving the signal-operating member into its operative position, and means set in motion by the movement of the signal-operating member from its normal position for holding it in such position for a predetermined time and then releasing it.

3. In a safety appliance for railway block systems in combination with a track and a train moving along the track, a signal on the train, coöperative signal-operating members on the train and track respectively,

the member on the track being normally out of the path of that of the train, additional contact members on the train and track respectively, the one on the track being normally in the path of that on the train for operation thereby as the train moves along the track, connections between the contact members on the track whereby the operation of the second named member moves the first named member into the path of its coöperative contact member on the train, an electric motor circuit having a normally open switch connected therein, a motor, a switch-operating member, means actuated by the contact members on the track for moving the switch-operating member to close the switch, a pawl movable into engagement with the switch-operating member to hold it in its closed position, and motor-operated means for tripping the pawl.

In witness whereof I have hereunto set my hand this 8th day of December, 1913.

STEPHEN A. MISCHANSKY.
